TWISTING DEVICE

Filed March 23, 1928

INVENTOR
W. J. LEACH

BY *W. J. Leach*

ATTORNEYS

UNITED STATES PATENT OFFICE.

WILLIAM J. LEACH, OF BURLINGTON, WISCONSIN.

TWISTING DEVICE.

Application filed March 23, 1928. Serial No. 264,080.

My invention relates to improvements in twisting devices, and it consists in the combinations, constructions, and arrangements herein described and claimed.

5 An object of my invention is to provide a twisting device in which improvements over my Patent No. 1,605,958, issued November 9, 1926, are embodied.

10 A further object is to provide a twisting device in which the body portion comprises two sections hingedly secured together, and in which the handles are secured to one of said sections, thereby providing a device which is convenient to handle and relatively 15 durable in construction.

20 A further object is to provide a twisting device of the type employing a two-piece die in which means is provided for automatically opening the device, whereby the sections of 25 said die will be separated.

Other objects and advantages will appear in the following specification, and the novel features of the invention will be particularly pointed out in the appended claim.

25 My invention is illustrated in the accompany drawings, forming part of this application, in which

Figure 1 is a side elevation of my device,

30 Figure 2 is a sectional view taken substantially along the line 2—2 of Figure 1, and

Figure 3 is a view showing a pair of the devices mounted upon a tube preparatory to twisting the latter.

35 In carrying out my invention, I make use of a body portion 1 having sockets 2 therein. A movable body portion 3 is hingedly secured at 4 to the portion 1. A spring 5 is provided for automatically moving the portion 3 into the dotted line position when a locking device 40 6 is moved from the full line position into the dotted line position.

45 The body portions 1 and 3 are provided with a transverse substantially rectangular opening 7 for the purpose of receiving a die comprising a pair of sections 8. The die sections 8 are slightly thinner than the portions 1 and 3 so that the die sections may be supported within a groove 9 provided in the portions 1 and 3, see Figure 2.

50 The sections 8 are provided with intersecting openings 10 within which a tube 11 may be disposed. The sections 8 are removably

supported within the grooves 9 by means of spring-pressed ball members 12. Handles 13 are disposed within the sockets 2.

55 From the foregoing description of the various parts of the device, the operation thereof may be readily understood. In Figure 3, I have shown a pair of the twisting devices applied to the tube 11. In operation when it is 60 desired to twist a tube, for instance, the device may be secured to the latter by moving the locking device 6 into the dotted line position, whereupon the spring 5 will automatically move the hinged portion 3 into the 65 dotted line position. At this time, the sections 8 are separated, since one of these sections moves with the portion 3 and the other is removably retained by the portion 1.

70 The device is now secured to the tube 11 by moving the portion 3 into contact with the portion 1 and securing the portions together by means of the locking device 6. When it is desired to remove the die sections 8, the device is opened up, whereupon the sections 8 75 may be removed by the hand by reason of the spring-pressed ball members 12.

I claim:

78 A twisting device comprising a body portion, a movable body portion hingedly secured to said body portion, a locking device for locking the movable body portion with respect to said body portion, said locking device being arranged to entirely disengage the movable body portion for releasing the latter, 85 spring means for moving said movable body portion away from said body portion when said locking device is released, said body portion and the movable body portion being provided with transverse openings arranged 90 to define a single opening when the movable body portion is locked to said body portion, a two-piece die, one of said die portions being slidably disposed within the opening in said movable body portion and the other of said 95 die portions being slidably disposed in the opening of said body portion, and yielding means associated with each of said body portions and arranged to yieldingly retain said die portions.

100 Signed at Burlington, in the county of Racine and State of Wisconsin this 19th day of March, A. D. 1928.

WILLIAM J. LEACH.
